UNITED STATES PATENT OFFICE.

WALFRID WALLENTHIN, OF ATTLEBORO, MASSACHUSETTS, ASSIGNOR TO THE ASSOCIATED ATTLEBORO MANUFACTURERS, INC., OF ATTLEBORO, MASSACHUSETTS, A CORPORATION OF MASSACHUSETTS.

DESIGN FOR A LIGHTER.

Application filed April 5, 1928. Serial No. 26,132. Term of patent 7 years.

To all whom it may concern:

Be it known that WALFRID WALLENTHIN, a citizen in the United States, residing at Attleboro, of the county of Bristol and State of Massachusetts, has invented a certain new, original, and ornamental Design for a Lighter, of which the following is a specification, reference being had to the accompanying drawing, forming a part thereof.

Fig. 1 is a side elevation of a pocket lighter embodying my new design.

Fig. 2 is an end elevation thereof.

Fig. 3 is a plan view thereof.

I claim,—

The ornamental design for a lighter substantially as shown.

In testimony whereof I affix my signature.

WALFRID WALLENTHIN.
